UNITED STATES PATENT OFFICE.

JOE D. ALLEY, OF EAGLE LAKE, TEXAS.

SAFETY DEVICE FOR HYDRAULIC PRESSES.

Application filed March 24, 1921, Serial No. 455,254. Renewed November 22, 1922.

To all whom it may concern:

Be it known that I, JOE D. ALLEY, a citizen of the United States, residing at Eagle Lake, in the county of Colorado and State 5 of Texas, have invented certain new and useful Improvements in a Safety Device for Hydraulic Presses, of which the following is a specification.

This invention relates to a safety device 10 for hydraulic presses and has for its principal object to provide means for preventing the ram from being forced from the cylinder in which same operates.

Another object of the invention is to provide means whereby bales may be formed 15 of a uniform desired size.

A still further object of the invention is to produce a safety device of this nature which will be of extremely simple, durable 20 and inexpensive construction, one which is efficient and reliable in operation and well adapted to the purpose for which it is designed.

With these and numerous other objects in 25 view, the invention resides in certain novel features of construction and the combination and arrangement of parts as will be hereinafter fully described and claimed.

In the drawing:—

Figure 1 is an elevational view of certain 30 portions of a hydraulic press, parts being shown in section, with my safety device attached thereto,

Figure 2 is a top plan view of the safety 35 device, and

Figure 3 is a sectional view taken through a portion thereof.

Referring to the drawing in detail it will 40 be seen that A represents the usual support upon which is mounted the cylinder B which slidably receives the ram C having mounted upon its upper end the block D. The water pipe E communicates with the cylinder B so that the water under pressure will force 45 the ram C upwardly. The parts thus far described are of conventional construction and well known in the art of hydraulic presses.

My invention consists in placing the valve 50 1 in communication with the pipe E by means of the union 2. This valve 1 is in communication with the return pipe 3 and it will be seen that when the valve is open the water under pressure will be relieved through the return pipe 3 and the upward movement of the ram C will stop.

This valve is controlled by the lever 4 pivoted on the bracket 5 and having the valve operating rod 6 pivoted to the lever 4 intermediate its ends. At the end of the lever 4 60 there is mounted the weight 7 which is preferably of cylindrical construction having a central bore extending therethrough for receiving the lever as shown in Figure 3. A conical shaped receptacle 8 is fixed to the 65 weight in any suitable manner. A chain is attached to the weight 7 so as to extend through the bottom of the conical shaped receptacle 8 and the other end of this chain 9 is attached to the follow block B. 70

The chain 9 will be of such a length so that when the ram C is in its lifted position as shown in Figure 1 the chain 9 will be taut and as the ram C is lifted upwardly from this point the chain 9 will pull upwardly 75 upon the lever 4 thus opening the valve 1 so that the water may return through the pipe 3 and thus the upward movement of the ram C will cease. When the pump is stopped which forces the water through pipe E the 80 ram C will be lowered and the weight 7 will close the valve 1 and particular attention is called to the utility of the conical shaped receptacle 8 which will receive the chain as the follow block moves downwardly toward 85 the lever 4 thus preventing the chain from catching into parts of the apparatus or other objects which may be positioned around the hydraulic press.

From the foregoing description, taken in 90 connection with the accompanying drawing, the construction and operation of the safety device will be readily understood without a more extended explanation. As numerous changes in form, proportion, and 95 in the minor details of construction may be resorted to without departing from the spirit of this invention, I do not wish to be limited to the construction herein shown and described other than as claimed. 100

Having thus described my invention what I claim as new is:

1. In combination with a ram of a hydraulic press, a safety device including a chain connected at one end to the ram, a 105 valve communicating with the intake pipe of the hydraulic press and the return pipe thereof, said chain being connected to said valve, for operating same in the manner and for the purpose specified. 110

2. A safety device to be used with hydraulic presses comprising a valve, a lever for

operating said valve, a weight situated upon the end of said lever, a receptacle situated on the lever, a chain attached to the lever so as to pass through the receptacle in the manner and for the purpose specified.

3. A safety device for hydraulic presses comprising a valve, an operating lever therefore, a weight situated on the lever so as to normally hold the valve in a closed position, a conical shaped receptacle situated on

the weight, a chain connected to the weight through the bottom of the receptacle in the manner and for the purpose specified.

In testimony whereof I affix my signature in presence of two witnesses.

JOE D. ALLEY.
